WIRE WRAPPING MACHINE

Constantine A. Caldes, Jersey City, N. J., assignor
to Anaconda Wire & Cable Company, New
York, N. Y., a corporation of Delaware

Application April 20, 1934, Serial No. 721,457

12 Claims. (Cl. 117—41)

My invention relates to apparatus for winding insulating material simultaneously about two or more wires to be later assembled into a cable having two or more separate insulated conductors.

Heretofore when a cable was to be built up by assembling two or more individual insulated conductors, each conductor has been wrapped with insulating material such as paper strip separately on a separate machine, and two or more of these wrapped conductors were then assembled into a cable on a separate machine. This required repeated handling of the separate conductors, once for each wrapping of each conductor, and then a separate handling during the assembly, and required a correspondingly extensive apparatus.

An object of my present invention is to provide a single machine in which two or more wires may be wrapped with insulating material separately and individually and assembled into a cable which may be again covered or wrapped with insulating material.

In simultaneously wrapping the two wires with paper or similar strip material, it is necessary, if the strip for either wire becomes broken, that the machine should stop as otherwise the wrapping of one wire and its assembly with an unwrapped uninsulated wire will continue, thereby using wire and insulating wrapping material to produce a cable having an uninsulated or defective conductor and which is, therefore, worthless. Accordingly, a further object of my invention is to provide means whereby the apparatus will be instantly stopped upon the breakage of insulation supply to either of the several wires being wrapped.

Further objects and features of the invention are to provide means for ironing the strip as it is wrapped about the wires, and to provide simple effective means for maintaining the required tautness on the material being wrapped.

The various features of the invention are illustrated in the accompanying drawings, in which—

Fig. 1 is a front elevation of a wrapping machine embodying a preferred form of the invention.

Fig. 2 is a detail plan view of a part of the control mechanism for stopping the machine.

Fig. 3 is a detail elevation of means actuated by the breaking of strip to actuate the stopping means.

Fig. 4 is a detail elevation, partly in section

and on a larger scale, of the wrapping mechanism.

Fig. 5 is a detail plan view of the mechanism shown in Fig. 4.

Figs. 6 and 7 are, respectively, cross sectional and longitudinal sectional views of a tensioning spring for the strip material.

Fig. 8 is a vertical detail view of the mechanism shown in Fig. 4 taken from the left of Fig. 4.

Figs. 9 and 10 are detail views taken from the same directions as Figs. 8 and 4, respectively, of strip guides serving to actuate a stopping means upon breakage of the strip, and

Fig. 11 is a detail view of an ironing element to secure a smooth uniform surface on the strip wrapped about the conductor wires.

The multiple wrapping mechanism of the present invention may be applied to assembling machines of various types. In the particular embodiment shown by way of illustration in the accompanying drawings, a pair of wires 12 and 13 are drawn upwardly from any suitable source below the base of the machine, then pass over guide pulleys 14 and 15 and through a central guide 16 which brings the wires together in position to be wrapped with an outer covering. The wires then pass upwardly through the supporting framework 17 of the apparatus and through a knitting mechanism 18 of any suitable type shown conventionally as mounted on the top of the frame 17. Thereafter the assembled cable 19 passes upwardly over an idler pulley 20 to the winding apparatus.

In the upward passage of the wires 12 and 13 they first pass through individual rotating sleeves 21, Fig. 4, rotatably supported by means of ball bearings 22 on bosses 23 of a supporting platform 24. Also mounted on the bearings 22 and rotating with the sleeves 21 are the hubs of horizontal gears 25 and 26, respectively, for the wires 12 and 13. The gears 25 and 26 also carry platforms 27 and 28, respectively, which rotate with the gears and carry the strip to be wrapped about the respective wires 12 and 13. The platforms 27 and 28 are secured in a unitary assembly with the sleeves 21, the platform 27 and the gears 25 by means of collars 29 and 30 enclosing the upper ends of the sleeves 21 and secured against the upper surfaces of the platform 28 by any suitable means such as a setscrew 31.

The gears 25 and 26 are simultaneously rotated in the same angular direction by means of a drive gear 32 between and meshing with the gears 55

25 and 26 and, in turn, supported on a rotatable shaft 33 which is driven through the bevel gears 34 and 35, shaft 36, bevel gears 37 and 38, shaft 39, bevel gears 40 and 41 (Fig. 1) from a main 5 drive shaft 42. The main drive shaft 42 may be driven from any suitable source such as the belt 43 and pulley 44 through a clutch 45 or other disconnecting mechanism.

The platforms 27 and 28 carry uprights 46 and 10 47 respectively upon which are rotatably mounted spools 48 and 49 of strip material to be wrapped about the wires 12 and 13 respectively. A length of strip 50 and 51, respectively, is led from the spools 48 and 49 to the surface of the 15 wires 12 and 13, first passing through respective eyelet guides 52 and 53 which serve to guide the strip to a quarter turn so that it will lie flat against the surface of the wire. When, therefore, the main driving shaft 42 is in motion and 20 rotates the platforms 27 and 28, the strip 50 and 51 passing from the reels 48 and 49 respectively to the wires 12 and 13 are caused to wrap about their respective wires and as these wires are drawn upwardly at the proper speed to form a 25 continuous spiral insulating covering for the wires. Suitable tension is applied to the reels 48 and 49 by means of tensioning wires 54 and 55 to cause the strips to wrap with the required 30 tautness about the wires and to avoid excessive tautness such as would cause breakage of the 35 strip. During the wrapping of the respective strips about their respective wires they are pressed to the required thickness and smoothed by means of ironing plates 56 and 57 mounted on plates 58 and 59 respectively mounted on posts 60 and 61 projecting upwardly from the respective 40 rotating tables 27 and 28. The ironing plates 56 and 57 are bent, as indicated in Fig. 11, so as accurately to position the wrapped wires with respect to the iron.

The lower ends of the eyelets 52 and 53 are secured to and support one of the ends of weight 45 ed levers 62 and 63 fulcrumed respectively on the posts 60 and 61 in such a manner that should either of the strips 50 or 51 break in passing from the spools or reels 48 or 49 to the wires 12 or 13, the weights 64 or 65 of the respective lever would drop, being no longer supported by the strip, thereby throwing the opposite end of the lever 63 upwardly and projecting a trip rod 66 or 67 upwardly through an opening in the plate 58 into a position to actuate a clutch throw-out or drive stopping device supported immediately above the plates 58. The actuating mechanism 55 for throwing out the clutch 45, or otherwise stopping the machine, is so positioned above the trip rods 66 and 67 that as the latter rotate with the tables 27 and 28, they pass beneath the actuating mechanism. When the rods 66 and 67 are pushed upwardly, however, because of the breakage of the strips 50 or 51, they strike against the actuating mechanism and displace the latter and, in this displacement, serve to throw out the clutch. The clutch throwout or stopping mechanism 60 comprises a branches lever 68 pivoted to swing horizontally on a bracket 69 of the frame 17 and held resiliently against a stop 70 by means of a tension spring 71.

The lever 68 is provided with two branches 72 and 73 from which contact pins 74 and 75 project horizontally above the rotating plates 58 and 59 at a sufficient height to permit the upper end of the trip rods 66 and 67 to pass beneath the rods 74 and 75, as indicated in Fig. 1, when the levers 62 and 63 are in normal position but

sufficiently close to the plates 58 and 59 that when either of the levers 62 or 63 is tilted by its respective weight 64 or 65 upon breakage of the strip 50 or 51, the rod 66 or 67 will be projected upwardly to a sufficient height to engage the rods 74, 75, as indicated in Fig. 3, during the rotation of the tables 27 or 28. As the respective trip rod 66 or 67 engages its respective rod 74 or 75, it swings the rod and the branched lever 68 counter-clockwise against the pivot of the 10 lever. As the lever swings counter-clockwise, it engages and displaces the lower arm of a lever 76 pivoted on a bracket on the frame 17 and held resiliently against the branched lever 68 by means of a spring 77. The upper end of the lever 76 is notched, as at 78, to receive a latch pin 79 of a vertical lever 80 which is resiliently held against the latch by means of a spring 81 between the lever 80 and bracket 82 on the frame 17. When the lever 76 is tilted counter-clockwise by 20 a counter-clockwise rotation of the lever 68, the upper notched end 78 is lowered, permitting the pin 79 to escape and permitting the lever 80 to be drawn clockwise.

The upper end of the lever 80 engages a horizontal lever 82, rotating the latter counter-clockwise when viewed in the direction of Fig. 2 and thereby disconnecting the clutch 45 through a link 83 connected to the opposite end of the lever 82.

It will thus be apparent that should either of the strips 50 or 51 break, its respective trip rod will immediately engage a pin of the trip lever 68 before completion of a revolution of the tables 27 and 28 and thereby swing the latch lever 76 35 and permit the spring 81 to throw the lever 80 to position to disengage the clutch. To again start the machine, the broken end of the strip must be secured to the surface of its respective wire so as to support the weight 64 or 65 and hold 40 the respective trip rod in disengaged position. Then, upon throwing the clutch levers 80 and 82 to engaging position, they will be received in and held by the latch lever 76 until a strip again breaks or, until the end of the strip is unwound 45 from its respective reel.

Any suitable mechanism may be used to maintain the required tension on the strips 50 and 51. In the form of the invention shown in Figs. 4, 6, 7 and 8, this tension is provided by a spring 54, 50 55, the lower end of which is formed into a cylinder 84 having end plates 85 and 86 and supported by a shaft 87 extending through the end plates 85 and 86, the plate 86 being rotatable relative to the cylinder and mounted in bracket bearings 55 88 and 89.

A coil spring 90 is positioned within the cylinder 84 and about the shaft 87 and one end 91 of this spring engages the cylinder 84, the other end being secured in the end plate 86. The plate 86 is rotated to wind the spring to the desired tension and then is held against unwinding by means of a pin 92 which may be inserted in any one of several radial sockets 93 and may rest against the base of the plate 27 or 28.

It will be understood that after the wires have been wrapped and brought together by passing through the guide 16, a strip of paper 94, or other material, drawn from a roll 95 may be folded about the assembled wires before they are covered by the fabric formed from the knitting elements 18. It will also be understood that when the clutch 45 disengages the main shaft 42 from the driving pulley 44, that the feeding of wire will also be stopped through any suitable mech- 75

anism. This mechanism is not illustrated as it forms no part of the present invention and may be of any conventional construction.

What I claim is—

5 1. A wire wrapping apparatus which comprises means to draw a plurality of wires simultaneously to assembled position, means to wrap strip helically about said wires individually as they pass to assembled position to form a continuous covering, and means to assemble said wires to a unitary structure after being placed in assembled position.

10 2. A wire wrapping apparatus which comprises means to draw a plurality of wires simultaneously to assembled position, means to wrap strip helically about said wires individually as they pass to assembled position to form a continuous covering, means to assemble said wires to a unitary structure after being placed in assembled position, and means to stop said wrapping mechanism upon the breakage of a strip passing to any of said wires.

15 3. A wire wrapping apparatus which comprises means to draw a plurality of wires simultaneously to assembled position, means to wrap strip helically about said wires individually as they pass to assembled position to form a continuous covering, means to assemble said wires to a unitary structure after being placed in assembled position, and means to iron and press said wrapped strip individually to a predetermined thickness on its respective wire.

20 4. A wire wrapping apparatus which comprises means to draw a plurality of wires simultaneously to assembled position, means to rotate individual supplies of strip material about said wires and to feed strip to said wires to wrap it about said wires as they pass to assembled position to form a continuous covering for said wires, means to assemble said wires, and means to stop said wrapping mechanism upon the breakage of said strip supply to said wires.

25 5. A wire wrapping apparatus which comprises means to draw a plurality of wires simultaneously to assembled position, means to rotate individual supplies of strip material about said wires to wrap strips of said material about said wires as they pass to assembled position to form a continuous covering for said wires, means to assemble said wires after being wrapped, means to stop said wrapping mechanism upon the breakage of strip from either of said strip supplies to its respective wire, said stopping mechanism comprising a trip mechanism supported by strip passing from its respective supply to wire and rotating with said supply about said wire, and a lever mechanism positioned to be engaged by said trip mechanism when the latter is unsupported and free from said trip mechanism when the latter is supported.

30 6. A wire wrapping apparatus which comprises means to draw a plurality of wires simultaneously to assembled position, means to rotate individual supplies of strip material about said wires to wrap strips of said material about said wires as they pass to assembled position to form a continuous covering for said wires, means to assemble said wires after being wrapped, means to stop said wrapping mechanism upon the breakage of strip from either of said strip supplies to its respective wire, said stopping mechanism comprising a trip mechanism supported by strip passing from its respective supply to a wire and rotating with said supply about said wire, a lever mecha-

nism positioned to be engaged by said trip mechanism when the latter is unsupported and free from said trip mechanism when the latter is supported, and a clutch disengaging mechanism actuated by the movement of said lever.

5 7. A wire wrapping apparatus which comprises means to draw a plurality of wires simultaneously to assembled position, rotating tables, one for each of said wires rotatable about the axes of said wires, means to rotate said tables simultaneously, and strip supply means mounted on said tables.

10 8. A wire wrapping apparatus which comprises means to draw a plurality of wires simultaneously to assembled position, rotating tables, one for each of said wires rotatable about the axes of said wires, means to rotate said tables simultaneously, strip supply means mounted on said tables, trip mechanisms, one for each of said supply means and mounted on its respective table, said trip mechanism being held against rotation by strip passing from said supply to its respective wire and released upon breakage of said strip, and means actuated by the release of said trip mechanism to stop the rotation of said tables.

15 9. A wire wrapping apparatus which comprises means to draw a plurality of wires simultaneously to assembled position, rotating tables, one for each of said wires rotatable about the axes of said wires, means to rotate said tables simultaneously, strip supply means mounted on said tables, trip mechanisms, one for each of said tables comprising a pivoted weighted lever, a strip eyelet and a trip pin, and means for stopping the rotation of said tables comprising lever mechanisms engaged in released position by said pins, and a clutch moved through said lever.

20 10. A wire wrapping apparatus which comprises means to draw a plurality of wires simultaneously to assembled position, rotating tables, one for each of said wires rotatable about the axes of said wires, means to rotate said tables simultaneously, strip supply means mounted on said tables, and means for tensioning strip on said supply, said tensioning means comprising a spring, and means for adjusting the tension of said spring.

25 11. A wire wrapping apparatus which comprises means to draw a plurality of wires simultaneously to assembled position, rotating tables, one for each of said wires rotatable about the axes of said wires, means to rotate said tables simultaneously, strip supply means mounted on said tables, and means closely spaced to said wire where said strip is being wrapped to press and iron said strip against said wire.

30 12. Trip mechanism for wire wrapping machines which comprises a rotating table having an opening for the passage of wire, a strip supply mounting means on said table, a weighted lever pivotally supported above said table and rotating therewith, a strip eyelet between said supply supporting means and the axis of said table to support the weight of said lever by the strip between said supply and said wire, a trip pin movable to actuating position by the release of said weight, an actuating lever mounted above said trip pin to be free from the latter when said weight is supported and to be engaged and tilted by said trip pin when the latter is moved by said weight, and means actuated by said trip lever to stop the rotation of said table.
